UNITED STATES PATENT OFFICE.

ALDEN E. OSBORN, OF NEW YORK, N. Y.

INTERNAL-COMBUSTION ENGINE.

1,212,391.

Specification of Letters Patent. Patented Jan. 16, 1917.

Application filed December 29, 1914. Serial No. 879,589.

To all whom it may concern:

Be it known that I, ALDEN E. OSBORN, a citizen of the United States of America, and a resident of New York, county and State of New York, have invented certain new and useful Improvements in Internal-Combustion Engines, of which the following is a specification, reference being had to the accompanying drawings, forming a part thereof.

My invention relates to internal combustion engines and one of the objects is to provide a four-cycle engine of this type, that shall be simple and compact in construction and efficient and powerful in operation.

A further object is to provide an improved valve construction which shall permit of a particularly advantageous arrangement of ports and which shall coöperate with the main piston in opening and closing the ports.

Another object is to provide an engine having a main working piston and a piston valve arranged to not only coöperate with the main piston in controlling the ports, but also to serve as an auxiliary power piston and thereby materially increase the economy of the engine.

Other objects and advantages of my invention will be set forth hereinafter, and in order that my invention may be thoroughly understood I will now proceed to describe the same in the following specification and then point out the novel features thereof in appended claims.

In my Patents Nos. 985,198; 987,164 and 1,011,480 and in my copending applications Serial No. 871,865 filed November 13, 1914, and Serial No. 878,853 filed December 24, 1914 I have shown and described valve mechanisms each comprising a main valve arranged to successively establish communication between the combustion chamber and two gas passages, and a secondary or auxiliary valve controlling one of the aforesaid passages in addition to the main valve. According to my present invention I employ two separate main valves (of which one is the engine piston) arranged to control the opening of two distinct passages into communication with the combustion chamber of the engine and an auxiliary valve which controls one of the aforesaid passages in addition to one of the main valves. For the

sake of simplicity in the engine structure the main piston of the engine, in addition to its usual function, is arranged to act as one of the main valves and controls one of the passages from the combustion chamber. Furthermore, the second valve member provided, controls not only the other main passage but also has the function of an auxiliary valve with reference to the passage controlled by the engine piston. By means of my present invention I therefore retain the advantages of my previous patents and applications above referred to as far as the valve functioning is concerned and at the same time obtain a very material advantage of simplicity in construction.

Referring to the drawings: Figure 1 is a sectional elevation of an engine having a piston valve, arranged and constructed in accordance with my invention. Fig. 2 is a similar view of a portion of a modified engine which is provided with a sleeve valve and which also embodies my invention. A view corresponding to Fig. 2 of another modification of my invention in which a different form of valve is employed, is shown in Fig. 3.

Having special reference to Fig. 1, the engine here shown comprises a cylinder 10 in which operates a piston 11, a crank shaft 12, a crank 13 which is connected to the piston by a rod 14, a crank casing 15, a valve cylinder 16 and a piston valve 17 therein. The piston valve is reciprocated at one-half the speed of the main piston by means of a valve crank 18 which is connected to the piston valve by a rod 19, and is secured to a crank shaft 20 which is operatively connected by sprocket wheels 21 and a chain 21^a or other suitable means, to the main crank shaft 12. The valve cylinder 16 communicates directly with the combustion chamber 22 of the main cylinder 10 at its outer end. There is, furthermore, a communicating passage 23 between the two cylinders at a material distance from the combustion chamber as clearly shown in Fig. 1.

The engine is provided with an exhaust port 24 and an admission port 25. The exhaust port is located nearer the end of the valve cylinder and is uncovered in a predetermined valve position so as to communicate directly with the combustion chamber.

The piston valve is provided with a trans-

verse passage 26 shown in dotted lines, which is adapted to establish communication between the admission port 25 and the passage 23 through which the fresh charge is admitted to the main cylinder during the latter part of the suction stroke.

The engine is shown as provided with the usual water-jacket 27 and the pistons have the usual rings 28 and 29.

10 Attention is particularly directed to the fact that the engine is very simple in construction, comprises a relatively few parts and does not require special auxiliary, admission or exhaust valves. This simplicity 15 in construction is attained by the particularly advantageous arrangement of ports whereby the main piston 11 co-operates with the piston valve in governing the admission port, as will be clearly understood from the 20 description of the operation of the device in the following paragraphs.

Assuming that the parts occupy the positions in which they are shown in the drawings, that a compressed charge has just been 25 fired and that the piston valve is reciprocating at one-half the speed of the main piston; the main piston will first move outwardly through its working stroke and the piston valve will advance in the same time 30 a distance corresponding to a ninety degree movement of the crank 18. When the main piston moves through about one-half of its working stroke, it uncovers the passage 23 but this port is previously covered by the 35 piston valve which in the same time has advanced a distance corresponding to about a forty-five degree movement of the crank 18. The next stroke of the main piston is the 40 exhaust stroke and during this stroke the piston moves a distance corresponding to another quarter turn of the valve crank. The arrangement of parts is such that the exhaust port is open at the beginning of the stroke, the burnt gases forced out, and the 45 exhaust port again covered. During the suction stroke of the piston which is next, the valve crank advances another quarter turn and the piston valve occupies a position approximately as shown in Fig. 1 but is 50 moving in the opposite direction toward the inner end of its stroke. The passage 23 is thus connected to the admission port 25. The fuel will then pass into the cylinder through this passage, there being of course 55 a partial vacuum formed in the combustion chamber during the first part of the suction stroke until the piston has advanced sufficiently to uncover the passage 23. The fuel is supplied in the usual way through the 60 remainder of the stroke. During the beginning of the compression stroke the admission port 23 is open but is soon closed by the piston valve which is moving over its inner center. Later in this stroke the 65 main piston covers this port and conse-

quently the fuel is prevented from being forced out into the carburetor when the piston valve again opens the passage.

My invention is applicable to an engine having a sleeve valve of the type shown and 70 described in my copending application Serial No. 878,853 filed December 24, 1914 and reference may now be had to Fig. 2 of the drawings, in which my invention is illustrated in this connection. The engine here 75 shown comprises a piston 30, which is surrounded by a sleeve valve 31 and is connected to the crank shaft 32 by a crank 33 and a connecting rod 34. The sleeve valve has a lateral projection 35 at its outer end which is connected to a valve crank shaft 36 by a valve crank 37 and a connecting rod 38. The shafts 32 and 36 are connected by gears 39. The cylinder of the engine comprises a body 40, an end member 41, and a pair of 80 interposed hollow annular members 42 and 43 in which the exhaust port 44 and admission port 45 are respectively located.

The parts of the cylinder are fitted together and certain of them are provided 85 with annular notches so as to provide pockets or grooves 45^a, 46 and 47 in which packing rings 48, 49 and 50 are located. The arrangement of parts is such that the ring 49 is interposed between the members 42 90 and 43 and between the exhaust and inlet passages. In this respect they correspond to the arrangement set forth in my copending application, to which reference has already been made. As explained in detail 95 hereinafter, the exhaust port 44 and the annular passage with which it communicates, are uncovered during the exhaust stroke on account of the displacement of the sleeve valve. On the other hand, the admission 100 port and the passage with which it communicates are opened into the cylinder through a plurality of radial openings 51 in the valve sleeve, the same being displaced to uncover the openings. 110

Attention is particularly directed to the fact that this engine is compact, while at the same time, the area of each of the admission and exhaust ports is relatively large and opens into the cylinder on all sides 115 through the annular passages. The sleeve valve during the first part of the compression stroke starts to move over its inner center and closes the admission port independently of the piston which closes the port 120 during the last part of this stroke and further prevents gas from being forced back into the carburetor.

The adaptation of my invention to an engine having a relatively long valve sleeve 125 of a well known type, is shown in Fig. 3. This arrangement differs from that of Fig. 2 in that the sleeve valve is provided with a passage 55, which registers with the exhaust port during the exhaust stroke. In 130

other respects this arrangement corresponds to that of Fig. 2 as far as the general arrangement and location of ports is concerned. The arrangement of annular passages similar to that shown in Fig. 2, may be employed in the structure of Fig. 3, if desired. Corresponding parts in this figure are designated by the same reference characters as those shown in Fig. 2 and further description of this structure or its operation is believed to be unnecessary.

Attention is particularly directed to certain distinguishing features and particular advantages of my invention as follows: The inlet passage opens into the cylinder at an intermediate point in the stroke of the piston and the valve is arranged to close the inlet passage independently of the piston.

Consequently the pressure of the explosion continues to do active work upon the piston, after the inlet passage has been uncovered by the main piston. Furthermore, the piston moves only part way out on the suction stroke before the inlet passage is open, thereby producing only a small vacuum which is an advantage. The piston has a material distance to move after the inlet passage is open before the completion of the suction stroke, thus allowing time for a larger volume of gas to enter the cylinder.

Furthermore, there is a material gain in compression because the slide valve closes the inlet passage and the cylinder on the compression stroke considerably in advance of the covering of the passage by the main piston.

In other words, I secure in an engine which is particularly simple in construction, the advantages which have hitherto only been obtained by the use of a far more complicated structure.

Other modifications may be effected without departing from the spirit and scope of my invention, and I intend that only such limitations be imposed as are indicated by the appended claims.

What I claim is:

1. An internal combustion engine comprising a cylinder having a combustion chamber at one end, a piston, an admission passage opening into the cylinder at an intermediate point in the piston stroke, a valve, and means for actuating the valve to open the admission passage in conjunction with the piston during the suction stroke and to close the admission passage independently of the piston at the end of the suction stroke.

2. An internal combustion engine comprising a cylinder, a piston, an admission passage at an intermediate point in the stroke of the piston, a combustion chamber, an exhaust port opening into the combustion chamber, a valve, and means for actuating the valve to independently control the

exhaust port, to open the admission passage in conjunction with the piston during the suction stroke and to close said passage independently of the piston at the end of the suction stroke.

3. An internal combustion engine comprising a cylinder having a combustion chamber at one end, a piston, an admission passage opening into the cylinder at an intermediate point in the piston stroke, an exhaust port, a piston valve, and means for operating the piston valve at one-half the speed of the main piston to independently control the exhaust port to open the admission passage in conjunction with the main piston during the suction stroke and to close said passage at the end of said suction stroke independently of the piston.

4. An internal combustion engine comprising a pair of parallel cylinders, a driven shaft, a piston in one of said cylinders operatively connected to the shaft, a piston in the other cylinder adapted to reciprocate at one-half the speed of the first piston, an admission port, an exhaust port opening into the cylinder of the slow-moving piston at a point intermediate the stroke of said piston, and a passage between the cylinders beyond which the fast moving piston travels, and means for operatively connecting the slow-moving piston to the shaft, whereby said slow-moving piston is arranged to close said passage at the end of the suction stroke before it is covered by the fast-moving piston.

5. An internal combustion engine comprising a main cylinder, a valve cylinder adjacent thereto and communicating therewith at one end, a passage between the two cylinders intermediate their ends, a main piston in the main cylinder, a piston valve in the valve cylinder connected to reciprocate at one-half the speed of the main piston, an exhaust passage opening into the valve cylinder and adapted to be uncovered when the piston valve is at the outer end of its stroke, an admission port opening into the valve cylinder, at an intermediate point in the piston stroke, said valve piston being provided with a transverse passage to establish communication between the admission port and the passage between cylinders during the suction stroke and to close said passage independently of the main piston at the end of the suction stroke.

6. An internal combustion engine comprising a cylinder having a combustion chamber, a passage extending through the cylinder wall at an intermediate point in the piston stroke, and a second passage into the chamber independently of the cylinder, a piston in said cylinder controlling the cylinder passage, a valve controlling both of said passages, and means for actuating the valve, arranged to retain the expansive pressure of combustion in the cylinder

whereby it continues to act upon the piston after the cylinder passage has been uncovered by the piston.

7. An internal combustion engine comprising a piston, a cylinder having two independent ports communicating therewith, one of which is at an intermediate point in the piston stroke, a valve and means for actuating the valve to open said intermediate port in conjunction with the piston during one stroke of the engine and to close said intermediate port independently of the piston at the end of the same stroke.

8. An internal combustion engine comprising a piston, a cylinder having two independent ports communicating therewith, one of which is at an intermediate point in

the piston stroke, a valve adapted to govern both of said ports, and means for actuating the valve to close the port while it is uncovered by the piston during one outward stroke of the piston, to uncover said port so that it is opened by the piston during the next outward piston stroke, and to close the port before it is again covered by the piston to close the cylinder during the following inward stroke of the piston.

In testimony whereof I have hereunto set my hand this 21st day of December, 1914, in the presence of two subscribing witnesses.

ALDEN E. OSBORN.
